(57) **CLAIM**

The ornamental design for a joist reinforcing bracket, as shown and described.

DESCRIPTION

FIG. 1 is a perspective view of a joist reinforcing bracket showing our new design;

FIG. 2 is an exploded perspective view thereof;

FIG. 3 is a rear elevational view thereof;

FIG. 4 is a front elevational view thereof;

FIG. 5 is a top view thereof;

FIG. 6 is a bottom view thereof; and,

FIG. 7 is an inverted left side elevational view with the right side being a mirror image thereof.

The broken line showing of a joist in FIGS. 1 and 3-7 is for illustrative purposes only and forms no part of the claimed design.
